MACHINE FOR PRINTING ON JARS

Donald W. Knaggs, City Island, N. Y., assignor to
 Anigraphic Process, Inc., New York, N. Y., a
 corporation of New York

Application July 28, 1937, Serial No. 156,067

9 Claims. (CL 101—40)

This invention relates to a new and useful improvement in printing press, and particularly a printing press to be used for printing on a hard uneven surface such as a glass jar, plastic or metal container. The machine may, of course, be used for printing on other surfaces, but is particularly adapted to use in printing on a surface which is more or less uneven and generally of a curved shape.

5 This application is related to application Serial No. 7,344, filed February 20, 1935 by John H. Friden for a "Machine for printing on bottles" now Patent No. 2,088,196, issued July 27, 1937. In fact, the present machine, so far as the printing press per se is concerned, is identical with the machine described in said patent. Reference may therefore be had to said patent for the details of mechanical construction. The present machine differs from the one described in said 10 patent in the mechanism for feeding the jars to printing position, holding them in position while being printed, and delivering them from the machine after having been printed.

15 The particular object of the present invention is to provide a machine which may be used to print on glass, plastic, or metal jars; cans, bottles, etc., which are continuously and rapidly fed through the machine, with one or more colors, by the offset method of printing.

20 If the surface of an ordinary glass jar such as is used in commerce for a large variety of commodities such as cosmetics, for example, is examined carefully, it will be noted that the surface instead of being smooth and regular as appears from the casual inspection, is actually quite uneven and irregular. In order to print evenly on such a surface it is therefore necessary to provide means for overcoming the irregularities of the surface itself. In a glass jar the hardness 25 of the surface presents an additional problem in this respect.

25 A feature of my invention is the provision of means for overcoming the irregularities in a surface, particularly the surface of a cylindrical or curved object such as a jar, so that a legend or label may be printed thereon evenly, smoothly and clearly.

30 The mechanism embodying this feature of my invention comprises means for holding a jar in resilient engagement with the transfer roller of an offset printing press, while permitting the jar to be rotated during the printing operation. In a machine such as described herein the difficulty of handling jars as they are passed through the 35 machine is naturally greater with smaller jars

than with larger ones. The difficulty of handling such objects is enhanced by the necessity for holding them in resilient engagement with the transfer roller.

35 Another feature of this invention therefore is the provision of means for passing jars through the machine rapidly and automatically in combination with mechanism which permits them to make resilient contact with the transfer roller of the machine.

40 Another feature of my invention is the provision of springs for holding an object such as a jar in resilient engagement with the transfer roller of an offset printing press.

45 Another feature of my invention is the provision of resilient means for holding the jars in engagement with the transfer roller in combination with means for rendering the transfer roller itself resilient in its engagement with a jar.

50 Another feature of my invention is the provision of means for feeding a jar or similar object to an offset printing press in such a manner that the feeding mechanism is stopped during the printing operation to permit the printing to be done, and then during a portion of the revolution 55 of the transfer roller of the press, operation of the feeding mechanism is resumed for removing the jar which has been printed, and for feeding a new jar to the printing position.

55 Still another feature of my invention is the provision of mechanism for intermittently feeding a succession of jars or similar objects to an offset printing press, combined with means for stopping said mechanism without damage to the mechanism or to the jars when the jars become 60 jammed, or for any other reason damage would result if the mechanism were not stopped.

65 Another feature of my invention is the provision of mechanism for holding a jar positively in position on a rotating arm while said arm holds the jar in resilient rotatable engagement with the transfer roller of an offset printing press.

70 A further feature of my invention is the provision of means for holding a jar positively in position as just described, combined with suitable mechanism for moving said means into and out of position in timed relation with the movement of the feeding mechanism and the transfer roller of an offset printing press.

75 Another feature of my invention is the provision of means permitting the same printing press and feeding mechanism to be used in printing jars of a variety of sizes.

Referring to the drawings:

Fig. 1 is a front view partly in section of my new machine as adapted to effect single color printing on jars or similar objects;

Fig. 2 is a side elevation partly broken away of the mechanism shown in Fig. 1;

Fig. 3 is a cross-sectional view along the lines 3—3 of Fig. 2;

Fig. 4 is an enlarged detailed view partly in section of my feeding turret illustrating the means whereby I hold a jar positively in position while permitting it resiliently to engage the transfer roller and to rotate while in such engagement, and further illustrating how my machine may be adapted to a variety of sizes of jars;

Fig. 5 is a view along the lines 5—5 of Fig. 4;

Fig. 6 is a sectional view along the lines 6—6 of Fig. 4;

Fig. 7 is a sectional view along the lines 7—7 of Fig. 4;

Fig. 8 is an enlarged sectional view along the lines 8—8 of Fig. 2;

Fig. 9 is a detail view illustrating the position of a jar at the time it is engaged by one of the 25 turret arms; and

Fig. 10 is a plan view of the feeding turret.

Similar reference numerals refer to similar parts throughout.

A suitable framework 1 is provided to which 30 the apparatus of the machine is attached. A slide 2 is mounted at the front of the machine and tilted at an angle such that the jars 4 will be fed to the machine by gravity. An endless conveyor belt 3 is provided on the other side of the machine, 35 which delivers the jars from the machine after they have been printed. The jars are fed to a position where they may be engaged by the arms 5, of a turret 6. The turret is rotated until it reaches the position shown in Figs. 2, 3 and 4, when it is momentarily stopped. The jar is then 40 in a position to be positively engaged by the ball bearing 7 mounted in the end of the arm 8. The arm 8 moves to the left, Fig. 2, to the position shown in Fig. 4, positively engaging the bottom of 45 the jar and holding it firmly in printing position on the arm 5.

As a jar is being picked up by an arm 5 and being brought to printing position the transfer roller is rotated so that when the jar is in printing 50 position the roller has come to a point where printing is to commence. The roller then engages the jar and as the jar is free to rotate, rotates the jar as the impression is printed thereon from the transfer roller. The arm 8 then retracts to the 55 position shown in Figs. 2 and 3, the turret 6 rotates another step carrying the bottle that has just been printed away from printing position and towards the delivery belt 3.

An arm 11, Fig. 3, is provided on which a bar 12 is mounted for sliding movement. The bar 12 terminates in the arm 8 having a ball bearing 7 mounted in the end thereof.

The motive power for the machine is provided by a motor 29, Fig. 3, which drives the machine in 60 the manner described in the application above referred to. As described in that application, there is a cam 42 mounted on the surface of a gear 39, which cam is engaged by a follower 43 mounted on an arm 44. The arm 44 is pivoted upon a support 45 and terminates in a fork which engages a pin 46 on connecting rod 47, which is journaled for reciprocating movement in a bushing 48. The rod 47 is secured to the bar 12 which is slidingly mounted on arm 11. A spring 49 which is secured to the frame 1 pulls the arm 44 toward the

machine, or upwardly in Fig. 3, whenever the follower 43 is not engaged by the cam 42.

After the printing has been completed on one jar the follower 43 engages cam 42 and moves the end of arm 44 downwardly, Fig. 3. This also 5 moves the rod 47, consequently the arm 8, downwardly and the jar which has been engaged by the ball bearing 7 is therefore free to move on and another jar may be moved in position on the next arm 5 to be engaged by the ball bearing 7. 10

Mounted on the front of the machine are two guide plates 13 and 14. The plate 13 has a bend at one end adapted to hold one jar in a position to be engaged by an arm 5. As an arm 5 enters the open end of a jar, it carries the jar with it 15 and the jar is gradually pushed on to the arm 5 by the plate 13 as the jar rises toward printing position. By the time the jar has reached the end of plate 13 it will ordinarily be properly in place on the arm 5, but in order to assure its 20 being in exactly the right position for printing it is engaged by the ball bearing 7 on arm 8, as heretofore described. After the jar has been printed the turret 6 moves on and the bottom of the jar engages the plate 14. As it moves down this 25 plate it gradually moves off of the arm 5 so that when the jar leaves engagement with the plate 14 it is in such a position that it will stand upright on the belt 3 and move away from the machine on this belt in an upright position as shown in Fig. 1. 30

The turret 6 is driven in intermittent rotary motion by the gear 15 mounted on the end of shaft 55, just as the spider of the above mentioned patent was driven in rotary motion by the shaft 55 of that patent. Arm 16 is secured to the 35 frame 1 and terminates in a collar 17 which encloses a bearing 18 in which is journaled a shaft 19. Shaft 19 terminates at one end in gear 20, which meshes with the gear 15. It is keyed to the frame of the turret 6 and held in position by 40 a nut 21. Between the collar 17 and the frame of the turret 6 are a plurality of shims 22 of varying thickness.

There are five arms 5 mounted on the turret. These arms are screwed onto a threaded projection 23 on a supporting member 24 which is mounted for rotation within a sliding block 25. Rotation is permitted by the use of ball bearings 26, mounted between an inner race 27 and an outer race 28. The block 25 is held in position by a 45 pair of supports 30 and 31 which are secured by bolts 32 to the frame of the turret. The block 25 terminates at its lower extremity in a threaded rod 33, and its upward movement is limited by a nut 34. Surrounding the rod 33 is a strong spring 35 which is held between the enlarged upper portion of the block 25 and the lower supporting member 31. The block 25 is therefore permitted to move downwardly against the resistance of the spring 35. When a jar is in printing position 50 therefore, and is engaged by the transfer roller of the press, it is held in such engagement by the spring 35, which permits a certain amount of downward motion to compensate for any irregularities in the surface of the jar.

The transfer roller of the press is also provided with a rubber blanket 36, Fig. 1, over which the printing surface is stretched with enough tension to provide a desired amount of resiliency of the surface itself due to the rubber blanket over 70 which it is placed. The springs 35, rubber blanket 36, as well as the rubber roller itself, all contribute to produce the necessary flexibility and resiliency to overcome the unevenness of the surface of a jar.

The machine may be adjusted for printing on jars of various sizes. If a larger jar is to be substituted for the jars 4, the arms 5 are unscrewed and arms of the correct size substituted by screwing them in position. As these arms will be centered at the same point as the previous arms, it is clear that when in printing position the outer surface of the jars would be raised to a higher point than those previously used. In order to provide for this the nut 21 and the frame of the turret 6 are removed, and one or more of the shims 22 taken from around the shaft 19. The frame of the turret is then replaced, and the nut 21 again screwed into position. The turret 6 will now be lowered enough to cause the outer surface of the jar 4 to be at the same height, and therefore in the same position with respect to the platen, as the surface of the smaller jars previously printed.

20 A sprocket 31 is rotated by a chain, not shown, in exactly the same manner in which an identical sprocket 31 is rotated by a chain 36, as shown and described in the above mentioned patent. The sprocket 31, Fig. 3, is keyed 25 to a shaft 50 which is journaled in bushing 51 mounted on a support 52. A disc 53 is mounted on the other end of shaft 50 and engages by friction a second disc 54 to form a friction clutch. The disc 54 is mounted on the shaft 55 which terminates in the gear 16, which turns the turret 6. A spring 56 surrounds the shaft 50 between the bushing 51 and disc 53 to provide the force necessary to maintain the friction discs 53 and 54 in contact. This mechanism is identical with 30 that shown in the above mentioned application, except, of course, for the turret structure with which the shaft 55 is associated on the printing side of the machine.

In the event a jar becomes lodged, or in any 40 other way the turret becomes jammed, the jamming will overcome the friction between the discs 53 and 54, so that the clutch will slip and thus prevent damage being done.

It is obvious, of course, that additional colors 45 may be supplied by providing additional impression cylinders, distribution rollers, ink supply, etc., similar to that shown in accordance with the usual practice in the prior art.

From the above description it will be apparent 50 that this invention involves certain principles of construction and operation which may be embodied in other physical forms. I do not, therefore, desire to be strictly limited to this disclosure, but rather to the scope of the appended claims.

55 What is claimed is:

1. A printing machine comprising means for feeding to the machine objects to be printed, an intermittently rotatable turret having a plurality of arms for picking up said objects and bringing them to printing position, means for positively holding said objects in proper printing position while said turret is stopped, and resilient supporting means for said arms to provide the proper printing pressure.

60 2. A printing machine comprising means for feeding objects to be printed to the machine, a

plurality of arms for picking up said objects, means for pushing said objects onto said arms, and means for resiliently supporting said arms.

3. A printing machine comprising a transfer roller, an arm mounted in spaced relation with said roller, a turret having a plurality of projections for feeding objects to be printed into printing position, means for periodically moving said arm into engagement with the object to be printed while in printing position, and means 10 for causing a resilient engagement between the object to be printed and the said roller.

4. In a printing machine, means for feeding generally cylindrical objects to be printed to said machine, means for delivering objects which have 15 been printed from said machine, means comprising a turret having a plurality of arms for picking up objects to be printed, carrying them to printing position, and then to said delivery means, and means cooperating with said turret arms for 20 assuring that said objects be placed in upright position on said delivery means.

5. A printing machine comprising a turret, a shaft inclined to the vertical axis of the machine on which said turret is mounted, a plurality of 25 arms on said turret adapted to engage objects of a particular internal size, said arms being removable and replaceable with others of different size to accommodate objects of different internal dimensions and means operable to adjust said 30 turret on said shaft to accommodate objects of different external dimensions.

6. A printing machine comprising a turret, a plurality of blocks mounted on said turret, a plurality of springs on which said blocks are mounted 35 to permit them to move relatively to the turret, and a plurality of arms mounted on said blocks, said arms being of a size to fit within the articles to be printed and to form the sole support for the articles during the printing operation.

7. A printing machine, means for feeding objects to be printed to said machine, a turret having a plurality of arms for engaging said objects, a plate mounted on said machine in such a position as to push the objects onto said arms, and a second plate mounted on said machine in such 45 position as to permit said objects gradually to leave said arms.

8. A printing machine comprising a turret having a plurality of arms adapted to engage objects to be printed, a shaft inclined to the vertical axis of the machine on which said turret is mounted, and means permitting said turret to be lowered or raised on said shaft to accommodate objects of varying sizes.

9. A printing machine comprising a turret having a plurality of arms adapted to engage generally cylindrical objects to be printed, a plate mounted on said machine in such a position as to push the objects onto said arms, delivery mechanism, and a second plate mounted on said machine in such a position as to permit said objects gradually to leave said arms, and be placed on said delivery mechanism in upright position.

DONALD W. KNAGGS.
